DESK PAD HOLDER

Richard McFadyen, Essex Fells, N.J., assignor to Ketcham and McDougall, Inc., Roseland, N.J., a corporation of New Jersey

Filed Sept. 6, 1963, Ser. No. 76,500

Term of patent 14 years

(Cl. D74—1)

FIG. 1

FIG. 2

FIG. 3

The broken line showing of a pad is merely for illustrative purposes; the dominant features of the design reside in the specific configuration and appearance of the pad holding clip portion as shown.

I claim:

The ornamental design for a desk pad holder, as shown and described.
